UNITED STATES PATENT OFFICE.

JOSEPHINE B. DANFORTH, OF CHATTANOOGA, TENNESSEE.

DESIGN FOR AN AUTOMOBILE SERVICE-FLAG.

57,512.

Specification for Design.

Patented Apr. 12, 1921.

Application filed September 20, 1918. Serial No. 254,997. Term of patent 3½ years.

To all whom it may concern:

Be it known that I, JOSEPHINE B. DANFORTH, a citizen of the United States, residing at Chattanooga, in the county of Hamilton and State of Tennessee, have invented a new, original, and ornamental Design for Automobile Service-Flags, of which the following is a specification, reference being had

to the accompanying drawing, forming part thereof.

The figure is a plan view of an automobile service flag showing my new design.

I claim:—

The ornamental design for an automobile service flag as shown.

JOSEPHINE B. DANFORTH.
